REAR SCREEN MOTION PICTURE PROJECTOR

Alex J. Procop, 18331 Parthenia St.,
Northridge, Calif. 91324

Filed July 2, 1971, Ser. No. 159,584

Term of patent 14 Years

Int. Cl. D16—02

U.S. Cl. D61—1

FIG. 1 is a front perspective view of a rear screen motion picture projector showing my new design.

FIG. 2 is a left side elevation thereof.

FIG. 3 is a rear elevation thereof.

The bottom view of the projector is substantially plain and unornamented.

I claim:

The ornamental design for a rear screen motion picture projector, substantially as shown and described.
